(57) **CLAIM**

The ornamental design for a perfusion enhancement controller case as shown and described.

DESCRIPTION

FIG. 1 is a front perspective view of a perfusion enhancement controller case showing our design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a rear view thereof.

Elements identified in broken lines in the accompanying drawings illustrate unclaimed portions of the article and form no part of the claimed design.
